UNITED STATES PATENT OFFICE.

EMIL A. HIRNER, OF ALLENTOWN, PENNSYLVANIA.

KNITTING-MACHINE.

1,023,312.

Specification of Letters Patent.

Patented Apr. 16, 1912.

Application filed December 12, 1908. Serial No. 487,131.

To all whom it may concern:

Be it known that I, EMIL A. HIRNER, of Allentown, in the county of Lehigh and State of Pennsylvania, have invented certain new and useful Improvements in Knitting-Machines, whereof the following is a specification, reference being had to the accompanying drawings.

My invention relates to a circular rib knitting machine, provided with means for automatically producing welts at intervals along a knit tubular web. Such machines are known as "welters". They produce welts composed of loose plain knitting united to the ribbed tubular fabric by having the loops of their terminal courses interlooped with alternate loops of the ribbed fabric. During the formation of the welts the dial needles are rendered inactive, and hold the tubular web which has previously been knit, while the cylinder needles proceed with knitting a welt section as plain knitting.

My invention comprises means for automatically effecting and controlling these operations, as well as means whereby the stitches of the cylinder needles are lengthened at the same time that the dial needles are rendered inactive.

In the embodiment of my invention which I have described, I employ a take-up mechanism, such as is ordinarily employed in machines of this type, and I have therefore omitted this part of the mechanism from the drawings. The take-up mechanism remains idle, except to hold the fabric under tension, as long as the dial needles hold the web during the formation of a welt. A difficulty commonly experienced in machines of this type, results from the crowding and chocking of the space between the cylinders after a few courses of the welt have been thus knit. According to my invention, I obviate this by employing pivoted jacks which are so shaped and actuated and which so co-act with contiguous parts of the machine, as to serve a two-fold purpose, acting not only to hold and feed the web during the production of ordinary tubular knitting, but also to deliver and roll back from the cylinder needles the welt courses as they are knit, at which time the fabric is under no tension from the take-up and therefore requires special means to keep the welt from crowding the needles. For this purpose I employ pivoted web holders mounted in the needle

cylinder and provided with forwardly and downwardly projecting noses, which in their inward motion co-act with the concaved surface of the dial plate, and thereby push the welt, as it is knit down against the previously knit tubular web which is held by the cylinder needles. These web holders correspond in general function to the so-called sinkers employed in ordinary circular stocking knitters, and other knitting machines where the feeding of the work requires other means than the ordinary weight or take-up; but, there is a special difficulty involved in the employment of sinkers or web holders in connection with the cylinder of a rib knitting machine. This results from the fact that sinkers are usually carried in a so-called "sinker ring", surrounding the top of the needle cylinder. In the ordinary stocking knitter such sinker rings are customarily employed, but they are not employed in connection with ribbers, because of the difficulty which arises when a needle in the cylinder is accidentally broken. To replace such broken needle it is necessary to withdraw it from its groove. This can easily be accomplished in the plain knitting machine, by removing the sinker ring; but in a rib knitter if an ordinary sinker ring were employed the removal would involve also the separation of the dial plate and its accompanying parts making the replacement of the broken needle an exceedingly difficult and tedious operation. To obviate this, while at the same time securing the advantage of a set of web holders co-operating with the needle cylinder, I have devised a special method of constructing and mounting the web holders in the needle cylinder itself, so that neither the web holders nor their operative cams afford any obstruction to the removal of a needle from the cylinder. To accomplish this the needle cylinder is provided with grooves for the reception of these web holders considerably deeper than the needle grooves and alternating with them. The web holders are vertical in position, are pivoted upon a fulcrum which lies within the circle of the needles, and are operated upon by cams sufficiently separated from the plane of the needles to permit the butt of a needle to pass up through its groove without interference by these cams.

My invention relates further to the automatic means for rendering the dial needles

inactive, while the cylinder needles knit the welts, together with means for simultaneously lengthening the stitches knit by said cylinder needles at this time. I further supply separate means for lengthening the stitch for the production of a loose course for transfer purposes quite independent of the means for lengthening the stitches during the knitting of the welt upon the cylinder needles. This is because special considerations apply to each of these regions requiring loose loops and the automatic lengthening of the stitches which will serve for one will not serve for the other.

15 In the accompanying drawings, Figure I, is a plan view of the upper portion of a machine embodying my invention. Fig. II, is a front elevation of the same. Fig. III, is a central vertical section taken on the line III, III, of Fig. I. Fig. IV, is a horizontal section taken on the line IV, IV, of Fig. III, showing the web holders and needle grooves together with means for pivoting said web holders. Fig. V, is a fragmentary sectional view of the machine showing the method of forming the welt. Fig. VI, is a fragmentary sectional view taken on line VI, VI, in Fig. III, and showing the cam for depressing the web holders. Fig. VII, is a sectional view of the fabric.

In said drawings, the bed plate 1, which may be mounted upon suitable standards, is provided with an annular groove 2, forming a bearing for an annulus 4. Said annulus 45 is mounted to rotate on the bed plate 1, and is formed with a depending circular rack 5, on its under side meshing with a suitable driving pinion, not shown. The annulus 4, is maintained in proper rotative relation 40 with the bed plate 1, by means of buttons 6, attached to said bed plate.

Mounted upon the annulus 4, is a cam cylinder 10, which is adapted to rotate therewith. Said cam cylinder 10, is provided on 45 its inner periphery with the cams usually employed in machines of this general class for cooperating with the needles, including a stitch cam which is vertically adjustable to vary the length of the stitches produced.

50 A needle cylinder 12, is mounted in stationary relation to the bed plate 1, and provided with radial grooves 14, for the needles 15, and radial grooves 16, for the web holders 17. The grooves 16, are cut deeper than the 55 needle grooves 14, but extend only for about one-half of the length of the needle cylinder. The needles 15, are maintained in their positions within the needle grooves of the cylinder 12, by an annular flange 22, upon the 60 upper edge of the cam cylinder 10. The web holders 17, are vertical in position, and are each provided on their inner edge with a notch 18, for the reception of a wire 20, which extends around the needle cylinder 12, 65 within the circle formed by the needles ly-

ing in a circumferential groove 21, formed in the needle cylinder. This wire acts as a fulcrum for the web holders 17, to rock upon. The web holders are provided with the usual web holding notches 19, and also with 70 downwardly and inwardly curved noses 23 with blunt or rounded ends, as best seen in Fig. V. These noses work over the upper edge of the needle cylinder, and by reason of the rocking motion of the web holders 75 upon their fulcrum, have a downward, as well as an inward motion, and so push the welts as they are formed away from the cylinder needles, in which motion they co-act with the opposing concaved peripheral 80 surface of the dial plate 35.

The web holders 17, are operated by an upper cam plate 24, mounted on cam ring 27, and a lower cam 25, the cam plate 24, coming into contact with the back of the 85 web holders above the point at which they are fulcrumed, and the cam 25, at a point below the fulcrum. These parts are best shown in Figs. I, V, and VI. The parts 90 above the fulcrum act to hold the upper ends 95 of the web holders, in their inner position, except where a recession of the cam surface 24, permits them to be rocked backwardly under the influence of the lower cam 25, which is pivotally mounted from the underside of the ring 27, and is maintained yieldingly in the path of the lower ends of the web holders, by the engagement of its laterally extending arm 28, with a spring plate 29, attached to the cam cylinder 10. This 100 lower cam 25, is adapted to tilt the upper end of each web holder outwardly as the adjacent cylinder needles are drawn down to form a stitch.

In order to permit the ready removal or 105 insertion of either the web holders or the needles, without dismantling the machine, I provide the cam ring 27, with a detachable segment or gate 90, which is located directly 110 above a notch 91, within the inwardly projecting annular flange 22, formed on the inner periphery of the cam cylinder 10. The said gate 90, of the cam ring 27, is pivoted about the screw 92, and is normally retained 115 in position by the screw 93, whose shank is received within a slot 95, in the swinging end of the said gate 90. By swinging back the said gate 90, any broken needle or web 120 holders may be readily withdrawn and new ones inserted in their stead by simply advancing the notch 91, to correspond with the 125 grooves which hold the injured needles or web holders. A vertical section through the parts just described is clearly shown at the left of Fig. III.

Mounted upon the cam cylinder 10, are two standards 30, and 31, supporting a yoke 32, from which is suspended a dial cam plate 34, arranged to rotate with said cam cylinder 10, and a dial needle plate 35, ar- 130

ranged to be retained in stationary relation with the needle cylinder 12, as by means of lugs, not shown. The dial cam and needle plates 34, and 35, respectively, are vertically adjustable with relation to the needle cylinder 12, by means of thumb nut 33.

Upon the under side of the cam plate 34, is a movable draw cam 36, which is connected by a post 37, with a link 38, pivotally connected to an arm 40. Said arm 40, is secured to an oscillatory vertical post 42, having a geared segment at its lower end, which meshes with a similar geared segment at the lower end of a vertical post 43. A cam arm 44, is secured to the post 42, and a cam arm 45, is secured to the post 43, said cam arms being adapted to be engaged and moved by a disk cam 50, mounted upon a plunger 51, which may be controlled in its vertical movement by any suitable form of pattern mechanism. When the arm 44, is engaged by the cam 50, it is swung inwardly, and with it the arm 40, and cam 36, connected thereto by the link 38. When said cam 36, is in this position, the dial needles are rendered inactive. When the arm 45, is engaged by the cam 50, it is swung inwardly, and the arm 40, together with cam 36, are moved outwardly, thus bringing the dial needles into action again.

Connected to the post 42, is an arm 46, having a link 47, connected to its swinging extremity. Said link 47, is also connected to a pivoted block 48. Said block is provided with two adjusting screws 52, and 53. The screws 52, coöperate with a plate 54, mounted upon the upper end of a plunger 55, which is connected to the above mentioned vertically movable stitch cam. By the adjustment of screws 52, and 53, the length of the stitches of the welt courses are regulated so that the horizontal welt tube is of the proper diameter with relation to the ribbed tube. The plate 54, is spring pressed upwardly by the spring 58, coiled about the post guide 59, mounted upon the cam cylinder. One end of the plate 54, is formed with a cam having the two bevel surfaces 70, and 61. The screw 53, coöperates with the bevel surface 60, to press the plate 54, downwardly, and with it the stitch cam.

It will be seen that by the connections above set forth, the cylinder stitch cam is lowered to lengthen the stitches knit by the cylinder needles simultaneously as the dial draw cam 36, is drawn inwardly, to render the dial needles inactive. So long as this condition is maintained the cylinder needles continue to knit the web 80, which comprises 60 courses of loose plain knitting, which is finally united to the ribbed fabric, by bringing the dial needles again into action.

Attached to the dial cam plate 34, is a thread guide plate 64, having the thread eye 65. In order to produce a loose course for

transfer purposes, the cylinder stitch cam may be moved downwardly, by the engagement of a screw 68, with the bevel surface 61, on plate 64. The screw 68, is mounted in a swinging arm 70, secured to a shaft 71, having a segmental gear at its lower end which meshes with a similar gear on the lower end of a shaft 72. Said shafts 71, and 72, have secured thereto, the cam arms 74, and 75, respectively, for coöperation with the disk cam 50, in a well known manner. It will be noted that the regulation of this loose course for transfer is quite independent of the means provided for loosening the stitch during the welt course. The screw 68, serves to regulate the length of the stitch for the transfer course, and the screw 53, serves to independently regulate the length of the stitch for the welt courses.

In the position of the parts as shown in Figs. I, II, and III, the machine is set for producing ordinary ribbed fabric. This continues until the roller cam 50, is raised to engage the arm 44, on the vertical shaft 42, by which the stitch cam for the cylinder needles is depressed and the dial cam 36, withdrawn, and the dial needles withdrawn, in the manner hereinbefore explained. This condition of the parts is shown in Fig. V. The retracted dial needles hold the web 79, while the welt courses 80, are loosely knit by the cylinder needles. During the knitting of these courses, the downwardly curved noses 23, of the web holders 17, in their inward motion, push the fabric tangentially against the main portion of the tube which is held under tension by the takeup mechanism. This action is facilitated by the opposing concavity of the peripheral surface of the dial plate. The curved noses of the web-holders reciprocate in the arc of a circle in contact with the outer fold of the welt as it forms. As soon as any considerable length of welt has been knit, the lower edge of the welt, where it returns upon itself, is more expansive than the other portions of the welt. The length of the curved noses of the web-holders is such (having regard to the normal length of a welt of this character), that as the welt approaches completion, the lower curved end of the nose engages and constantly tends to push the expanded lower end of the welt down. In this way the noses of the sinkers without any pointed or projecting portion which might enter the fabric, and which as it reciprocates might therefore tend to draw up as well as down, effectually feeds the welt away from the needles, preventing crowding. I have heretofore referred to the unusual depth of the slots which receive the web holders. This feature also tends to increase the efficacy of the web holders with their long downwardly curved noses, to effectually force the welt as it is formed away

115

120

125

130

from the needles. After a predetermined interval of time, the roller cam 50, is again raised to the level of and to engage cam arm 45, on shaft 43, whereupon the machine is again thrown into its original position to produce tubular ribbed knitting. After knitting about a dozen ravel courses, the cam 50, is raised to the level of cam arm 75, to engage it to depress the cylinder stitch cam, as hereinbefore explained, for knitting a course of loose knitting, for marking the line upon which the fabric is to be cut or transferred. After this the roller cam 50, is again raised to the level of the arm 74, to engage it, whereupon the parts just mentioned again resume their initial position, for the continuation of ribbed knitting. These operations are successively and automatically repeated, as by any well known 20 pattern chain or pattern wheel mechanism, and result in the production of ribbed string-work, with horizontal welt tubes occurring at regular intervals, determined by the adjustment of the pattern mechanism 25 which controls the motion of the roller cam 50.

It will be remembered that there are only half as many stitches in the welt, as there are in the ribbed tube, hence the reason for depressing the cylinder stitch cam, for enlarging the loops produced by the cylinder needles during the knitting of the welt. This results in giving the welt band the same elasticity as is possessed by the ribbed portion of the tube, and also prevents any crowding of the tube at the region of the welt which would otherwise occur.

Having thus described my invention, I claim:—

40 1. In a rib knitter, a needle cylinder provided with grooves for the web holders; a fulcruming projection within each groove; a series of web holders with notches engaging said projections and fulcrumed thereon; and coördinate cam surfaces acting continuously upon the backs of the web holders one above and the other below the fulcrum by the combined action of which the web

holders are held in place and positively operated as levers of the first class. 59

2. In a rib knitter, a needle cylinder provided with grooves for the web holders; a fulcruming surface within said groove; a series of web holders fulcrumed thereon; coördinate cam surfaces acting upon the backs of the web holders, one above and the other below the fulcrum, by the combined action of which the web holders are positively operated as levers of the first class; and an opening in the upper cam surface 60 protected by a pivoted gate affording facility for the removal of any web holder from its groove.

3. In a rib knitting machine, the combination of a dial plate having a movable 65 draw cam and means for retracting the draw cam to render the dial needles inactive during the formation of the welt courses upon the cylinder needles; a cam cylinder provided with a stitch cam and automatically 70 operated means for operating the stitch cam to produce loose transfer courses upon the cylinder needles; and independent automatically operated means for operating the stitch cam to produce loose welt courses. 75

4. In a rib knitting machine, the combination of a cam cylinder provided with a stitch cam, and automatically operated means for operating the stitch cam to produce loose transfer courses; a separate and 80 distinct automatically operated means for operating said cam to produce loose welt courses; a dial plate having a movable draw cam and means for retracting the said cam to render the dial needles inactive during 85 the formation of the welt courses upon the cylinder needles; and connections between the two last mentioned means whereby both operations take place simultaneously.

In testimony whereof, I have hereunto signed my name, at Philadelphia, Pennsylvania, this third day of December, 1908.

EMIL A. HIRNER.
